FLUID FUEL BURNER

Philip P. Shoenberger, Oakland, Calif.

Application October 18, 1932, Serial No. 638,319½

5 Claims. (Cl. 158—110)

My invention relates to a fluid fuel burner and more particularly to one for burning natural gas. The burner may be used for heating furnaces and for general purposes, but is suited more particularly for repair work on boilers, locomotives and plate work.

Objects of the invention are to provide a burner of simple construction, and having a minimum of parts arranged to be easily taken apart and assembled and to provide a burner in which the fuel and air for combustion may be quickly and thoroughly mixed to obtain a concentrated, intense flame.

The various features of the invention are illustrated in the accompanying drawing, in which

Fig. 1 is a longitudinal view, partly in section, of a burner embodying a preferred form of my invention;

Fig. 2 is an end view of the burner;

Fig. 3 is a side view of a nozzle pipe forming part of the burner, and

Fig. 4 is a cross section of the burner taken on line 4—4 of Fig. 1.

In the preferred embodiment of the invention shown in the accompanying drawing, the burner comprises a fuel chamber 10 in a suitable casting 11, to which fuel gas may be supplied through a passage 12 from either a pipe 13 entering the back of the casting or from pipes 14 or 15 entering the side. Inlets not used are to be plugged. The passageway 12 preferably delivers to the chamber 10 at the side of the latter. Air for combustion, supplied under pressure from either of two pipes 16 one entering the back of the casting and the other entering the side, is delivered through a passage 18 through a rear wall of the chamber 10 and in alignment with a threaded outlet opening 19 in the front wall of the chamber.

The air supplied under pressure through the passage 18 does not mix in the chamber 10 with the fuel gas supplied thereto but enters an inner or air nozzle pipe 20 which has one end 21 enlarged and shaped to fit the edge of the passage 18 and extends through the chamber 10 and outlet opening 19 and projects forwardly of the casting 11. The gas supplied through the passage 12 is received in an annular compartment 22 formed in the chamber 10 about the pipe 20. The outlet opening 19 is of larger diameter than the outside diameter of the inner pipe 20 thereby forming an annular outlet opening from the chamber 10. An outlet nozzle pipe 23 is threaded into the outlet 19 and is sufficiently larger in diameter to form with the inner pipe 20 an annular outlet gas passage 24.

The gas passage 24 is constricted at its outer end by an enlargement 25 of the inner pipe 20 which is thickened gradually from its delivery end, to provide a tapering, outer surface, and by a tapering or curving of the delivery end of the outer nozzle toward the tapered end of the inner nozzle. The outer tapered end of the outer or gas nozzle is slit longitudinally from its delivery end to form a peripheral series of spaced longitudinal slots 26 through which the gas issues in such manner as to mix immediately with the surrounding air. The gas and surrounding air are immediately drawn forwardly into the air jet issuing from the inner pipe 20 which creates a forward inward suction about the end of the nozzle.

The width of the slots 26 may be varied somewhat by threading the nozzle 23 into the opening 19 to a greater or less degree thereby to spring the areas between the slots to a greater or less degree against the tapered area of the pipe 20 and widen the slots or permit them to contract.

Projections 27 may be formed on the inner surface of the tapered end area of the outer nozzle 23 so as to space the latter from the inner nozzle thereby forming narrow converging passageways 28 for a part of the gas stream. To prevent the flame from being blown out, spaced pilot openings 29 are provided back of the slots 26 through which small pilot jets of gas may issue. Some of the openings 29 may be placed in an annular groove 30.

The above invention provides a burner of great simplicity, only three parts being required. It may be taken apart by merely unscrewing the nozzle 23 from the opening 19, whereupon the inner pipe 20 which is merely placed against the outlet of the passage 18 may be easily removed. Access to all of the passages is then easily available. The burner may be readily assembled by placing the inner pipe 20 in position and threading the end of the nozzle 23 into the opening 19. The action of the air jet from the air pipe 20 combined with the preparatory mixing of the gas about the burner tip with the surrounding air is capable of causing a very quick and thorough mixing and a sharp intense flame to be attained. The sharpness and intensity of the flame may be controlled by controlling the air and gas supply.

Having described my invention, what I claim is:

1. A fluid fuel burner comprising a chamber having an outlet, an air inlet aligned with said outlet and a gas inlet, an air nozzle extending from said air inlet through said chamber and

- 5 said outlet and spaced therefrom to form a surrounding gas passage and projecting from said outlet and having an outwardly projecting enlargement tapered to its outlet end, a gas nozzle 5 threaded into said outlet and spaced from said air nozzle to form an annular gas passage, the outer end of said gas nozzle being turned toward the tapering area of said enlargement to contract said gas passage and having longitudinal outlet slits.
- 10 2. A fluid fuel burner comprising a chamber having an outlet, an air inlet aligned with said outlet and a gas inlet, an air nozzle extending from said air inlet through said chamber and said outlet and spaced therefrom to form a surrounding gas passage and projecting from said outlet and a gas nozzle threaded into said outlet and spaced from said air nozzle to form an annular gas passage, the outer end of said gas nozzle being turned toward said air nozzle to contract said gas passage and having longitudinal outlet slits, said air nozzle being unsecured in said chamber and held in position therein by being confined between the air inlet and the taper of the gas nozzle.
- 15 3. A fluid fuel burner comprising a chamber having an outlet, an air inlet aligned with said outlet and a gas inlet, an air nozzle extending from said air inlet through said chamber and said outlet and spaced therefrom to form a surrounding gas passage and projecting from said outlet and a gas nozzle threaded into said outlet and spaced from said air nozzle to form an annular gas passage, the outer end of said gas nozzle being turned toward said air nozzle to contract said gas passage and having longitudinal outlet slits and having spacer pins between said slit part of said gas nozzle and said air nozzle.
- 20 4. A fluid fuel burner comprising a chamber having an outlet, an air inlet aligned with said outlet and a gas inlet, an air nozzle extending from said air inlet through said chamber and said outlet and spaced therefrom to form a surrounding gas passage and projecting from said outlet, the outer surface of the projecting end of said nozzle being contracted toward said end, and a gas nozzle threaded into said outlet and spaced from said air nozzle to form an annular gas passage, the outer end of said gas nozzle being turned toward said air nozzle to contract said gas passage, said air nozzle being unsecured in said chamber and spacing projections between said fuel nozzle and the contracted surface of the air nozzle and spaced about the latter at a distance from the exit end thereof and bearing against the contracted end of said air nozzle to hold the latter in position against said air inlet.

CERTIFICATE OF CORRECTION.

Patent No. 1,969,157.

August 7, 1934.

It is hereby certified that the name of the inventor in the heading to the printed specification of the above numbered patent was erroneously printed as "Philip P. Shoenberger", whereas said name should have been printed as Philip D. Shoenberger, as shown by the records of the case in this office; and that the said Letters Patent should be read with this correction therein that the same may conform to the record of the case in the Patent Office.

Signed and sealed this 2nd day of October, A. D. 1934.

Leslie Frazer
